CLAIM

The ornamental design for tableware, as shown and described.

DESCRIPTION

FIG. 1 is a top perspective view of tableware, showing my new design;

FIG. 2 is a bottom perspective view thereof;

FIG. 3 is a front elevation view thereof;

FIG. 4 is a rear elevation view thereof;

FIG. 5 is a right side elevation view thereof, the left side elevation view being mirror symmetrical thereto;

FIG. 6 is a top plan view thereof;

FIG. 7 is a bottom plan view thereof;

FIG. 8 is a sectional view thereof, taken along 8-8 of FIG. 3;

FIG. 9 is a front elevation view thereof, showing the tableware stacked on additional exemplary tableware; and, FIG. 10 is a top perspective view of FIG. 9.

The broken lines illustrate unclaimed environmental features that form no part of the claimed design.

1 Claim, 5 Drawing Sheets(56)
